UNITED STATES PATENT OFFICE.

SAMUEL H. CONWELL AND CLARENCE W. COURT, OF CHICAGO, ILLINOIS, ASSIGNEES
TO WALTER P. MURPHY, OF NEW YORK, N. Y.

RAILWAY-CAR OF THE GONDOLA TYPE.

1,384,183.

Specification of Letters Patent.

Patented July 12, 1921.

Application filed February 15, 1919. Serial No. 277,265.

To all whom it may concern:

Be it known that we, SAMUEL H. CONWELL and CLARENCE W. COURT, citizens of the United States, residing at Chicago, in the county of Cook and State of Illinois, have invented certain new and useful Improvements in Railway-Cars of the Gondola Type, of which the following is a specification:

10 Our invention relates to the construction of railway cars, and particularly to railway cars of the gondola type, and the invention has for its primary object to provide an all steel end wall panel for a car of this sort, together with means for attaching the same to the side walls and under frame of the car, whereby the end of the car will have the strength and rigidity necessary to withstand the stresses and pressures which are exerted 20 against it when the car is in service.

The invention consists of the new and improved constructions, arrangements and devices to be hereinafter described and claimed for carrying out the above stated objects 25 and such other objects as will appear from the following description of certain preferred embodiments of our invention.

The invention is illustrated in the accompanying drawings, wherein—

30 Figure 1 is an end elevation of the body of a gondola car constructed in accordance with our invention.

Fig. 2 is a plan view of the same.

Fig. 3 is a fragmentary sectional plan, on an enlarged scale, taken on line 3—3 of Fig. 1.

Fig. 4 is a fragmentary plan view of the corner of the car.

Fig. 5 is a vertical sectional view on line 40 5—5 of Fig. 3.

Fig. 6 is a sectional plan on line 6—6 of Fig. 5.

Fig. 7 is a fragmentary side elevation of the car.

45 Fig. 8 is a vertical section on line 8—8 of Fig. 1.

Fig. 9 is a fragmentary view, in perspective, of a sheet steel end wall panel.

Fig. 10 is a vertical sectional view on line 50 10—10 of Fig. 8, the scale being enlarged.

Fig. 11 is a view similar to Fig. 9, showing a modification.

Fig. 12 is a plan view, with parts broken away, showing a modified form of the invention adapted particularly for cars of 55 steel construction.

Fig. 13 is an end elevation of the construction shown in Fig. 12.

Fig. 14 is a fragmentary side elevation, and—

55 Figs. 15, 16 and 17 are sectional views taken on lines 15—15, 16—16 and 17—17 respectively, of Fig. 13.

Like characters of reference designate like parts in the several figures of the drawings.

Referring first to the construction shown in Figs. 1 to 10 inclusive, 25 indicates the end sill of the car, 26 the side sills, 27 the draft sills and 28 the dead wood. The walls 70 of the car shown at 29 are of wood and are strengthened and reinforced by side stakes 30. The flooring of the car is indicated at 31.

The end panel consists of a sheet of steel 75 32 which extends across the car from side to side and is formed preferably with integral flanges 33 along its vertical edges which overlap and are secured to the side walls 29 of the car by any suitable fastening devices, 80 such as bolts 34. The end sheet is formed with a plurality of preferably horizontal corrugations 35 which merge one into the other so that the corrugated portion of the panel has a sinuous configuration which, in effect, constitutes of the panel a series of beams, of equal strength, for transmitting 85 thrusts on the end of the car to the side walls thereof. It will be understood that the end of a car, due to inertia of the cargo, 90 is subjected to very heavy thrusts and pressures, particularly when the train starts and stops. In a gondola car, especially when fully loaded with material in bulk, such as coal, sand, ore, gravel, and the like, the pressure 95 on the ends of the car may be very great and as a result it frequently happens that gondola car ends are bulged and bent out and sometimes broken by the forces exerted against them.

In the construction shown in Figs. 1 to 10 inclusive, a construction suitable particularly for cars built largely of wood, the sheet steel end panel is attached to the side walls and under frame of the car by means of attaching members which, coöperating with the corrugations formed in the sheet, prevent the deflection of the end wall of the car under cargo stresses.

- 10 The lower edge of the end sheet 32 is bent so as to provide a flange 36 which preferably intervenes between the flooring of the car and the end sill, being attached to the latter by bolts 37. The flanges 33 on the 15 vertical edges of the sheet extend down below flange 36, the lower portions thereof, indicated at 38, overlapping and being secured by bolts 39, for example, to the under frame of the car. These flanges; therefore, 20 form, in effect, corner stakes. The structure at the corner of the car is further reinforced by means of a vertically disposed angle 40 riveted to the end sheet and secured against the inner surface of the side wall by the 25 bolts 34 above referred to.

The top chord at the end of the car is made very strong and rigid so that it will not be bent or otherwise injured when heavy articles are loaded over the end of 30 the car or when, as sometimes happens, some long, heavy article rests on the end wall of the car in transit. The top chord is also called upon to restrain the upper edge of the end sheet and it is important to make it 35 very strong and rigid. In order that a load against the end sheet should not produce deflection thereof, we form a flange 41 at the upper edge of the end sheet, this flange being preferably integral with the sheet. 40 To the flange is secured an angular top chord member 42, the vertical leg 43 of which is secured, at each end, to the side wall of the car by an angular strap 44 bolted to the upper side sheathing board by 45 bolts 45. At each lower corner is arranged an angle brace 46 secured to the end sill by bolts 47 which pass through the lower flange 36 of the end sheet, the upright leg of this angle being riveted at 48 to the angle member 40 above referred to.

To further strengthen the end structure of the car against cargo thrusts and pressures, we provide a pair of diagonally arranged tie rods 49, one at each side of the 55 car, the upper end of each rod extending through the end sheet and through an anchoring casting 50 riveted to the end sheet and being provided with a nut 51. The lower end of the rod, preferably flattened 60 as indicated at 52, is bolted at 53 to the side sill 26 of the car and is riveted at 54 to an angular anchoring member 55 secured by bolts 56 against the under side of the side 65 sill. Preferably horizontally disposed tie rods 57 anchor the lower portions of the end

panel to the side stakes 30. These tie rods also pass through the vertical angle members 40 arranged at the corners of the car.

A modified construction is shown in Fig. 11. The end sheet 32^a is formed on its vertical edges with flanges 33^a which increase in width from top to bottom. This gives the flange, considering it as a corner stake, very considerable rigidity and increases its spread at the bottom so that it may be attached, for example, by bolts 58 to the side sill 26^a.

In Figs. 12 to 17 inclusive, we have shown a modified embodiment of the invention intended particularly for gondola cars of steel construction although certain features of this structure might be employed to advantage in connection with a steel end for cars composed otherwise largely of wood. The end sheet 59 is formed at its vertical 85 edges with flanges 60 overlapping the side wall sheets 61 of the car. Preferably the corners are reinforced by means of vertically disposed angular members 62. The lower edge of the end sheet is riveted at 90 63 to an end sill plate 64. The end sill plate is cut away at 65 for the draw bar (not shown) and a striking casting 66 is riveted thereto at this place. The lower edges of the end sill plate 64, on opposite 95 sides of the striking casting, are reinforced by angles 67. Angles 68 are riveted to the lower edge of the end sheet and to the sill plate by a line of rivets 69. These angles support the floor sheets 70.

A novel form of top chord member is shown as forming part of the modified construction illustrated in these figures; although this form of top chord might be employed, if desired, in connection with 105 the construction previously described. The upper edge of the end sheet 59 is formed so that when flanged over a flange 71 is provided which is relatively wide at the middle of the car and diminishes in width toward 110 the sides. The top chord member, preferably an angle bar 72, is bent to conform, generally speaking, to the edge of the flange 71 and is riveted to said flange. Corner gussets 73 connect the top chord 72 on the 115 end wall of the car with the top chords 74 of the side wall sheet 61.

While we have shown certain preferred embodiments of our invention, one construction being intended particularly for wooden 120 cars and another for cars composed of steel, and while there is a coöperative relation between the several features of our invention, having reference to our primary object, namely, the provision of a gondola 125 car end which will be both light in weight and at the same time capable of resisting the stresses to which this part of a car is subjected when in service, it will be realized that certain features of the invention might 130

be employed in combinations different from those shown and described. We wish it to be understood also that the invention might be otherwise modified, as to details of construction, without departure from the scope of the invention as defined by the claims hereto appended.

We claim:

1. In a railway car of the gondola type, the combination with the underframe and side walls of the car, of vertical rigidifying elements at the ends of said side walls, a top chord member across the end anchored to said side walls, and a sheet steel end wall panel secured to said underframe, vertical rigidifying members and top chord, and formed with horizontally disposed corrugations which extend substantially to and terminate near the vertical rigidifying members.
2. In a railway car of the gondola type, the combination with the underframe and side walls of the car, of vertical rigidifying elements at the ends of said side walls, a top chord member across the end anchored to said side walls, and a sheet steel end wall panel secured to said underframe, vertical rigidifying members and top chord, and formed with horizontally disposed corrugations which extend substantially to and terminate near the vertical rigidifying members and merge one into the other whereby the panel is made up in effect into a plurality of beams of substantially equal strength extending across the car from side to side.
3. In a railway car of the gondola type, the combination with the underframe and side walls of the car, of a sheet metal end panel formed with rigidifying corrugations, means for attaching said panel to the side walls and underframe of the car, and a top chord member attached to said panel and forming therewith a channel-shaped structure at the upper edge of the end wall of the car and means for anchoring the ends of the top chord member to the side walls of the car.
4. In a railway car of the gondola type, the combination with the underframe and side walls of the car, of a sheet metal panel formed with rigidifying corrugations, means for attaching said panel to the side walls and underframe of the car, and a top chord member attached to said panel and forming therewith a channel-shaped structure at the upper edge of the end wall of the car which is relatively wide at the middle of the car and diminishes in width toward the sides.
5. In a railway car of the gondola type, the combination with the underframe and side walls of the car, of a sheet metal end panel formed with rigidifying corrugations and with an angularly disposed flange at its upper edge, means for attaching said panel to the side walls and underframe of the car, and a top chord member angular in cross-section attached to said side walls and to the flange at the upper edge of the panel.
6. In a railway car of the gondola type, the combination with the underframe and side walls of the car, of a sheet metal panel formed with rigidifying corrugations and with an angularly disposed flange at its upper edge which is relatively wide at the middle and diminishes in width toward the sides of the car, means for attaching said panel to the side walls and underframe of the car, and a top chord member angular in cross-section bent to conform to the configuration of the flange at the upper edge of the panel and secured thereto.
7. In a railway car of the gondola type, a metal wall sheet formed with a flange at its upper edge relatively wide at the middle and tapering in width toward the edges of the sheet, in combination with a top chord member angular in cross-section, bent to conform to the shape of said flange and secured thereto to provide, with the sheet, a channel-shaped reinforcement at the upper edge of the wall of the car.
8. In a railway car of the gondola type, the combination with the underframe and side walls of the car, of a sheet steel end wall panel formed on its lower edge with a flange secured to said underframe, on its vertical edges with the flanges attached to said side walls, and with a flange at its upper edge, and a top chord member secured to said last-named flange and anchored at its ends to the side walls of the car.
9. In a railway car of the gondola type, the combination with the side sills, end sills and side walls of the car, of a sheet steel end wall panel formed along its vertical edges with flanges which overlap and are attached to said side walls and project downwardly along and are anchored to said side sills and along its lower edge with a flange anchored to said end sill.
10. In a railway car of the gondola type, the combination with the side sills, end sill and side walls of the car, of a sheet steel end wall panel formed along its lower edge with an inwardly turned flange anchored to the end sill and along its vertical edges with flanges which are relatively narrow at the top and increase in width toward the bottom of the sheet, and which overlap and are attached to the side walls of the car and extend downwardly and are anchored to said side sills.
11. In a railway car of the gondola type, the combination with the side sills, end sill and side walls of the car, of a sheet steel end wall panel formed with horizontal corrugations of substantially equal width equally spaced apart and merging one into the other.

along its lower edge with an inwardly extending flange anchored to the end sill and provided along its vertical edges with flanges which overlap and are attached to said side walls and extend downwardly along and are anchored to said side sills.

12. In a railway car of the gondola type, the combination with wooden end sill, side sills and side walls, of a sheet metal end panel secured to said side walls and having a flange at its lower edge anchored to said end sill, anchoring members secured to the under sides of the side sills, and tie rods engaged with said panel and extending diagonally downward and attached at their lower ends to said anchoring members.

13. In a railway car of the gondola type, the combination with the wooden side sills, side stakes and side walls, of a sheet metal end panel secured to said side walls, angular anchoring members secured to the under sides of said side sills, and tie rods passing through and engaging the marginal portions of said panel and extending diagonally downward and attached at their lower ends to said anchoring members and means for anchoring the lower portion of said panel to said side stakes.

14. In railway car of the gondola type, the combination with the underframe and side walls of the car, of an end panel provided with means constituting flanges for

attachment to said side walls, a top chord member anchored to the side walls and secured to the upper edge of said panel, and tie rods passing through and anchored to the marginal portions of said panel just below said top chord and extending diagonally downward and anchored to said underframe.

15. In combination with the wooden end sill, side sills and side walls of a gondola car, of a sheet steel end panel formed with horizontal corrugations of substantially equal width, equally spaced apart and merging one into the other, said panel being provided at its lower edge with a flange secured to said end sill, at its vertical edges with flanges overlapping and secured to said side walls and side sills, and at its upper edge with a substantially horizontal flange, a top chord member angular in cross-section, secured to said last-named flange, angular straps for anchoring the ends of the top chord member to the side walls of the car, angular corner post members secured to the face of the end panel and to the flanges thereof through the side walls, anchoring members on said side sills, and diagonally arranged tie rods engaging said panel on opposite sides directly below the top chord and attached at their lower ends to the anchoring members on the side sills.

SAMUEL H. CONWELL.
CLARENCE W. COURT.
